[57] ABSTRACT

A power amplifier for low-frequency oscillations, realizable by integrated-circuit technique, comprises a

number of cascaded transistors forming a high-impedance input stage, an intermediate or driver stage and a balanced power stage feeding a central output terminal 12. A control transistor T_2 constituting part of a composite input transistor T_1, T_2 has its collector grounded through a current-limiting transistor T_4 paired with an identical transistor T_5 producing an image current which duplicates the collector current of the control transistor T_2 and passes through a voltage divider composed of a pair of resistors R_6, R_7 each of the same magnitude as a feedback resistor R_8 inserted between the output terminal 12 and the emitter of transistor T_2 . A controlled transistor T_3 at the entrance of the intermediate stage, of the same conductivity type (PNP) as the control transistor T_2 and substantially identical therewith, has its base connected to the collector of transistor T_2 and has its emitter energized through an ancillary transistor T_9 of opposite conductivity type whose base is tied to the junction of resistors R_6 and R_7 . The emitters of transistors T_3 and T_9 are interconnected via a further resistor R_9 of the same magnitude; with the bases of twin transistors T_4 and T_5 jointly connected to a d-c supply terminal 1 through a biasing transistor T_{10} and a low resistance (e.g. diodes D', D'') equaling the overall emitter/base resistance of composite transistor T_1, T_2 , this arrangement stabilizes the means voltage of output terminal 12 at substantially half the voltage of the ungrounded supply terminal 4.

LOW FREQUENCY POWER AMPLIFIER

SPECIFICATION

My present invention relates to a power amplifier for low-frequency oscillations.

An object of this invention is to provide an amplifier of this type which can be readily realized by integrated-circuit technique as a module adapted, when used in conjunction with a limited number of external circuit elements, to supply a variety of loads with maximum output power when energized from a given source of direct current.

A more specific object is to provide an amplifier of this description whose operating point (d-c output voltage in the absence of an a-c input signal) remains substantially equal to half the d-c supply voltage even if the latter is subject to fluctuations.

An amplifier according to my invention comprises, essentially, an input stage, an intermediate or driver stage and a balanced power stage constituted by cascaded transistors. One transistor of the input stage, hereinafter referred to as the control transistor, has a base connected to receive the a-c input signal (advantageously through an emitter-follower transistor energizing it in a Darlington configuration), a collector transmitting that signal to the intermediate stage and an emitter tied to a central output terminal of the power stage through a feedback resistor whose magnitude is large compared with the forward emitter/base resistance of this control transistor. The collector of the control transistor, whose base receives an a-c signal to be amplified, is connected to a preferably grounded supply terminal through a current-limiting transistor and is also tied to the base of a substantially identical controlled transistor of the same conductivity type (e.g. PNP) whereby the base currents of the control and controlled transistors substantially balance each other. In this manner, the emitter current of the control transistor (drawn through the feedback resistor) varies symmetrically about an average value so as to hold the mean voltage of the output terminal substantially at a median value between the potentials of the supply terminals, i.e., at about half the voltage of the ungrounded supply terminal if one of these terminals is grounded.

In accordance with another feature of my invention, the current-limiting transistor in series with the control transistor is one of a pair of identical twin transistors whose mate draws an image current, duplicating the collector current of the control transistor, through a voltage divider biasing an ancillary transistor inserted in the emitter lead of the controlled transistor. More particularly, this voltage divider consists essentially of two series resistors each having the same magnitude as the feedback resistor, the junction of these series resistors being tied to the base of the ancillary transistor which is of a conductivity type (e.g. NPN) opposite that of the controlled transistor and has its emitter connected to that of the latter transistor through a fourth resistor of the same magnitude. The bases of the twin transistors are advantageously connected to the ungrounded supply terminal through a biasing transistor whose base is connected directly to the collector of the twin transistor generating the image current, the biasing transistor lying in series with a relatively low resistance which may be constituted by the forward resis-

tance of one or more diodes and which substantially equals the forward emitter/base resistance of the control transistor. If, according to a preferred embodiment, the control transistor forms part of a composite transistor connected in a Darlington configuration, this low resistance should have a value equaling the overall emitter/base resistance of the composite transistor which generally is twice the individual emitter/base resistance of the control transistor itself.

Pursuant to still another feature of my invention, the power stage of the amplifier includes two pilot transistors of opposite conductivity types having their bases connected to the collector of the last transistor of the driver stage, these two pilot transistors working into respective final transistors of identical conductivity type (e.g. NPN) whose emitter-collector circuits extend between the central output terminal and respective terminals of the d-c source. One of these pilot transistors, i.e. the one energizing the final transistor whose emitter is joined to the central output terminal, may also be connected to that final transistor in a Darlington configuration so as to have an emitter-follower effect preventing its saturation over a wide swing range of one polarity of the a-c input signal; a similar dynamic for the other signal polarity may be realized by inserting an additional transistor in series with the other pilot transistor in a feedback path from the central output terminal, the additional transistor and the associated pilot transistor being of opposite conductivity types and having their emitters directly interconnected.

The above and other features of my invention will be described in greater detail hereinafter with reference to the accompanying drawing in which:

FIG. 1 is a circuit diagram of an amplifier according to the invention; and

FIG. 2 is a similar circuit diagram showing a modification.

The amplifier shown in FIG. 1 is essentially an integrated circuit IC with a number of terminals 1, 3, 4, 6-10 and 12. A switch SW, in its illustrated position, interconnects terminals 1 and 3 so as to short out a pair of diodes D₁ and D₂ inserted between these terminals. A second switch SW', ganged with switch SW, connects a condenser C₁ across terminals 4 and 12 in the illustrated position; upon reversal of switch SW, terminal 1 is connected to terminal 4 (rather than to terminal 3) so as to short-circuit a resistor R₂₀. Terminal 1 carries positive supply voltage +E from a direct-current source whose grounded negative pole is connected to terminals 9 and 10. The amplifier output is developed across terminals 10 and 12, the latter having a voltage V_{out} which in the quiescent state is half the supply voltage +E as will be shown later on. An alternating input voltage V_{in} is delivered to terminal 8 through a resistance R_s representing the internal impedance of the signal source. Terminal 6 is grounded for high frequencies through an external capacitor C_e in series with a resistor RF serving as a negative-feedback impedance for the input stage of the amplifier.

The input stage of the amplifier comprises a pair of PNP transistors T₁, T₂ connected in a Darlington circuit, the base of transistor T₁ being joined to input terminal 8 through a resistor R₁. Transistor T₂, which is the control transistor referred to above, has its emitter connected by way of a feedback resistor R₈ to output terminal 12, resistor R₈ lying in the only direct-current path between this emitter and the supply terminal 1.

Two serially connected resistors R_6 and R_7 , of the same magnitude R as resistor R_8 , are joined directly to terminal 3 and through the forward resistances of the cascaded diodes D_1 , D_2 to terminal 1.

A pair of twin NPN transistors T_4 and T_5 , with grounded emitters and interconnected bases, form respective branches of a current generator also including a biasing transistor T_{10} whose collector is energized from high-voltage terminal 4 through a diode D_6 . The emitter of transistor T_{10} is connected by way of two cascaded diodes D' , D'' to the bases of transistors T_4 , T_5 and to the grounded input terminal 9 via a resistor R_5 maintaining the twin transistors in a state of predetermined conductivity. The base of transistor T_{10} is tied to the collector of transistor T_5 and to resistor R_7 . Transistor T_4 , whose collector is tied to that of transistor T_2 , establishes a constant collector current for the latter transistor which is always conductive but prevented from saturation by virtue of its emitter-follower connection to feedback resistor R_8 . Transistor T_5 draws an identical image current through the voltage divider constituted by resistors R_6 and R_7 .

It will be noted that the input signal V_{in} is applied to transistor T_1 , without the intermediary of any coupling capacitor, thereby not only eliminating an external component but also suppressing low-frequency distortion and signal delays upon cut-in. Also, the high input impedance of the Darlington circuit T_1 , T_2 can be fully utilized by connecting the signal source V_{in} across terminals 8 and 9 without the interposition of an external voltage divider. The negative feedback afforded by resistors RF and R_8 further increases the dynamic input resistance.

The collector of control transistor T_2 is tied to the base of a controlled transistor T_3 of PNP type which is the entrance transistor of an intermediate stage also including a Darlington-type compound NPN transistor T_{11} , T_{12} in cascade therewith. The emitter of transistor T_3 , whose collector (like that of transistor T_1) is grounded, is connected through a resistor R_9 of magnitude R to the emitter of an ancillary NPN transistor T_9 having its base connected to the junction J of resistors R_6 , R_7 and having its collector energized directly from supply terminal 1. This supply terminal is also connected directly to the collector of the transistor T_{11} . Transistor T_{12} , which is the last transistor of the intermediate stage, drives two pilot transistors T_{15} (PNP) and T_{16} (PNP) of the output stage of the amplifier working into respective power transistors T_{21} , T_{22} , both of NPN type. Transistor T_{21} has its collector joined to supply terminal 1 and its emitter tied to output terminal 12 as well as to the collector of transistor T_{22} whose emitter is grounded. Biasing resistors R_{17} and R_{18} are connected in the base/emitter circuits of transistors T_{21} and T_{22} , respectively.

Two further current-limiting PNP transistors T_7 and T_8 have their emitters connected in parallel to ancillary supply terminal 4 and have their bases energized from that terminal through the forward resistance of diode D_6 . Transistor T_7 feeds the transistor T_{12} through a diode D_{14} whose forward resistance provides a voltage differential between the bases of pilot transistors T_{15} and T_{16} . Transistor T_8 supplies operating current to transistors T_2 and T_{22} and also applies a biasing potential to the base of an additional transistor T_{17} of NPN type whose emitter is tied to that of the PNP pilot transistor T_{16} . Transistor T_{17} , whose collector is energized

directly from supply terminal 1, has its base/emitter circuit included in a feedback loop which extends from the collector of transistor T_{22} (and therefore from output terminal 12) through three cascaded diodes D_{18} , D_{19} , D_{20} by way of transistors T_{17} and T_{16} to the base of transistor T_{22} .

In operation, an input signal V_{in} impressed upon terminal 8 is transmitted via cascaded transistors T_1 , T_2 , T_3 , T_{11} and T_{12} to pilot transistors T_{15} , T_{16} in parallel, 10 these two pilot transistors modulating the conductances of final transistors T_{21} and T_{22} in a balanced manner so that the output voltage on terminal 12 varies in the same sense as the input voltage. A negative signal on terminal 8, for example, drives the base of transistor T_{15} T_{21} negative and the base of transistor T_{22} positive so as to lower the voltage V_{out} on terminal 12; this latter voltage is degeneratively fed back through resistor R_8 to the emitter of control transistor T_2 , thereby further increasing the input resistance of the composite transistor T_1 , T_2 . The increased current flow through transistor T_{22} also drives the base of transistor T_{17} more negative so as to reduce the positive emitter potential of transistor T_{16} which thereby tends to follow the lowering of its base potential in response to the input signal. 20 A similar emitter-follower effect is also experienced by transistor T_{15} whose emitter potential is lowered by the feedback through biasing resistor R_{17} . This prevents the saturation of transistors T_{15} and T_{16} during positive and negative half-cycles, respectively.

25 As illustrated in FIG. 2, the biasing diodes D' and D'' can be replaced by an adjustable resistor R_4 in series with fixed resistor R_5 to facilitate manual variation of the matching currents traversing transistors T_4 and T_5 . FIG. 2 also shows that diodes D_6 , D_{14} and D_{18} – D_{20} can be replaced by the forward base-emitter resistances of respective transistors T_6 , T_{14} , T_{18} , T_{19} and T_{20} ; transistors T_6 , T_{18} and T_{19} have their collectors directly joined to their bases whereas transistors T_{14} and T_{20} have biasing resistors R_{13} and R_{15} inserted in their collector/base and base/emitter circuits, respectively. Transistors T_6 and T_{18} are of PNP type, transistors T_{14} , T_{19} and T_{20} being of NPN type.

30 In the following more detailed analysis of the mode of operation of my improved amplifier I shall use the following symbols;

V_{bek} — the forward base/emitter resistance of any transistor T_k (k being a generic subscript); thus, V_{be5} is the base/emitter resistance of transistor T_5 .

35 V_{cek} — the collector/emitter voltage of a transistor T_k (with the postscript sat indicating a state of saturation);

I_{ck} — the collector current of any transistor T_k ;

I_{ek} — the emitter current of such transistor;

I_{bk} — the corresponding base current;

40 V_d — the voltage drop across any forwardly biased diode.

45 Let us now consider the collector current I_{c5} of transistor T_5 under the simplifying assumption that all transistors have a current gain of infinity, i.e., that their base current is zero. We can then write

$$I_{c5} = E - V_{be5} - 2V_5 - V_{be10} \quad (1)$$

50 and, in view of the identical bias of transistors T_4 and T_5 ,

$$I_{e2} = I_{c2} = I_{c4} = I_{c5}$$

(2)

In the quiescent state, in which the input voltage of terminal 8 is zero, we can also write

$$V_{out} = V_o = V_{be1} + V_{be2} + RI_{e2}$$

(3)

From equations (1), (2) and (3) it follows that

$$V_o = V_{be1} + V_{be2} + E - V_{be5} - 2V_d - V_{be10}/2$$

(4)

If $V_{bek} = V_d$, equation (4) simplifies to

$$V_o = E/2$$

(5)

Looking back at equation (1) we find that the collector current I_{c5} of matching transistor T_5 has two components, the first of these components having a value $E/2R$ depending only upon the supply voltage; the voltage drop across resistor R_8 due to the second component compensates the emitter potential of transistor T_2 . These components also appear in current I_{c21} .

Equation (5) is valid only for the assumed case of very high current gain. In many practical instances, however, the base current of transistor T_2 cannot be neglected, particularly in the case of transistors of the epitaxial type having a relatively low current-amplification factor. In that case, with $I_{e2} = I_{c2} + I_{b2}$, equation (5) is modified to read

$$V_o = E/2 + RI_{b2}$$

(5')

The error due to the term RI_{b2} , however, can be compensated by the base current of transistor T_3 which has essentially the same structure as transistor T_2 . With

$$I_{e2} = I_{c2} + I_{b2} = I_{c4} - I_{b3} + I_{b2} = I_{c5} - I_{b3} + I_{b2}$$

(6)

we find that

$$V_o = E/2 + R(I_{b2} - I_{b3})$$

(7)

which for $I_{b2} \approx I_{b3}$ reduces to equation (5). Since $R_6 = R_9 = R$, the emitter current of transistor T_3 is given by

$$I_{e3} = E - V_{be9} - V_{be11} - V_{be12}/R - I_{c5}$$

(8)

wherein the first right-hand term differs from the value of $2I_{c5}$, as per equation (1), only by the negligible amount V_{bek}/R wherein V_{be} is of substantially the same magnitude as V_d . It follows that $I_{e3} \approx I_{c5}$, i.e. the emitter current drawn by the first transistor T_3 of the intermediate stage substantially equals the image current passing through transistor T_5 . The finite current gain of transistors T_9 and T_{10} can be compensated by the adjustment of resistor R_4 (FIG. 2) replacing diodes D' and D'' .

In the alternate position of switches SW and SW' , with the connection between terminals 1 and 3 interrupted, diodes D_1 and D_2 introduce a voltage drop equal to $2V_d$. With resistor R_{20} short-circuited, the upper limit of the voltage swing on output terminal 12 has the value $E - V_{be21} - V_{be15} - V_{ce9}(\text{sat})$ whereas the lower limit is the voltage $V_{ce22}(\text{sat})$. The mean V_m of these values is given by

$$V_m = E - V_{be21} - V_{be15} - V_{ce7}(\text{sat}) + V_{ce22}(\text{sat})/2 \quad (9)$$

which, if the saturation voltages of transistors T_1 and T_{20} are substantially equal, reduces to

$$V_m = E - V_{be21} - V_{be15}/2 \quad (10)$$

The reduction of the image current I_{c5} by the value $2V_d/2R$, due to the presence of diodes D_1 and D_2 , makes the quiescent output voltage V_o substantially equal to the voltage V_m as per equation (10).

Terminal 7 may be used to place a biasing or modulating voltage upon the bases of transistors T_9 and T_{10} .

The function transistor T_7 is somewhat analogous to that of transistor T_4 in limiting the collector current of transistor T_{12} to an approximately constant magnitude, with the base currents of transistors T_{15} and T_{16} substantially balancing each other. Transistor T_8 supplies the necessary base current to transistor T_{17} ; its contribution to the currents drawn by transistors T_2 and T_{22} is minimized by the lowering of the potential of ancillary supply terminal 4 in the illustrated switch position through the voltage drop introduced by resistor R_{20} . Shunt capacitor C_1 holds the voltage of terminal 4 substantially constant in the face of varying current flow through dropping resistor R_{20} ; in the alternate position of switches SW and SW' , in which terminals 1 and 4 are at the same potential, this capacitor is not needed.

I claim:

1. A power amplifier comprising an input stage including a control transistor, an intermediate stage including a controlled transistor of the same conductivity type as said control transistor, and a power stage including a pair of final transistors serially connected in balanced relationship between a central output terminal and respective supply terminals of a source of direct current, each of said transistors being provided with an emitter, a base and a collector, said output terminal being connected to the emitter of one and to the collector of the other of said final transistors, the collector of said controlled transistor being connected to one of said supply terminals;

coupling means in said power stage for connecting the bases of said final transistors in push-pull to said intermediate stage;

a resistive direct-current feedback connection extending from said output terminal to the emitter of said control transistor, the base of said control transistor being connected to receive an a-c signal to be amplified, the collector of said control transistor being connected to the base of said controlled transistor;

a current-limiting transistor connected in series with said control transistor between the collector of the latter and said one of said supply terminals for

- maintaining an emitter current in said control transistor holding the mean voltage of said output terminal substantially at a median value between the potentials of said supply terminals, the emitter of said control transistor being conductively joined to the other of said supply terminals by way of said feedback connection;
- an ancillary transistor connected in series with said controlled transistor between the emitter thereof and said other of said supply terminals;
- a matching transistor duplicating said current-limiting transistor and generating an image current equal to the collector current of said control transistor, said current-limiting transistor and said matching transistor having interconnected bases and having their emitters connected to said one of said supply terminals; and
- biasing means for said ancillary transistor connecting the base thereof to the collector of said matching transistor.
2. A power amplifier as defined in claim 1 further comprising a voltage divider extending between the collector of said matching transistor and said other supply terminal, the base of said ancillary transistor being tied to a junction of said voltage divider.
3. A power amplifier as defined in claim 2 wherein said voltage divider comprises two identical resistors forming said junction, the resistance of each of said resistors equaling that of said resistive feedback connection.
4. A power amplifier as defined in claim 3 wherein said ancillary transistor is of a conductivity type opposite that of said controlled transistor and has its emitter connected to the emitter of said controlled transistor through a further resistor of the same magnitude as said identical resistors.
5. A power amplifier as defined in claim 4 wherein said current-limiting and matching transistors are provided with a common biasing transistor having an emitter connected to their bases, a collector connected to said other supply terminal and a base tied to the collector of said matching transistor.
6. A power amplifier as defined in claim 5, further comprising resistance means between said interconnected bases and the emitter of said biasing transistor, said resistance means having a magnitude which is small compared with that of the resistance of said feedback connection.
7. A power amplifier as defined in claim 6 wherein said control transistor is part of a composite transistor connected in a Darlington configuration with an overall forward emitter/base resistance substantially equal to the magnitude of said resistance means.
8. A power amplifier as defined in claim 5, further comprising a voltage-dropping resistor inserted between said other supply terminal and the collector of

- said biasing transistor, the bases of said final transistors being provided with biasing circuits extending through said voltage-dropping resistor to said other supply terminal.
9. A power amplifier as defined in claim 8, further comprising a capacitive shunt between the collector of said biasing transistor and said output terminal.
10. A power amplifier as defined in claim 8, further comprising diode means inserted between said voltage divider and said other of said supply terminals with a forward resistance of substantially the magnitude of said resistance means.
11. A power amplifier as defined in claim 1 wherein said intermediate and power stages are connected to provide negative feedback through said resistive connection to the emitter of said control transistor.
12. A power amplifier as defined in claim 1 wherein said coupling means comprises a first pilot transistor of one conductivity type in cascade with said one of said final transistors, and a second pilot transistor of the opposite conductivity type in cascade with said other of said final transistors, said pilot transistors having bases connected to an output lead of said intermediate stage, said final transistors being both of said one conductivity type.
13. A power amplifier as defined in claim 12, further comprising a biasing diode connected between the bases of said pilot transistors.
14. A power amplifier as defined in claim 12 wherein said power stage further includes an additional transistor in series with said second pilot transistor having a base/emitter circuit connected between said output terminal and the emitter of said second pilot transistor for preventing saturation of the latter.
15. A power amplifier as defined in claim 14 wherein said first pilot transistor and said one of said final transistors are connected in an emitter-follower circuit.
16. A power amplifier as defined in claim 14 wherein said additional transistor is of the same conductivity type as said first pilot transistor and has an emitter connected to the emitter of said second pilot transistor.
17. A power amplifier as defined in claim 12 wherein said output lead is connected to a collector of a transistor in said intermediate stage, further comprising another current-limiting transistor connected between the last-mentioned collector and said other supply terminal.
18. A power amplifier as defined in claim 1 wherein said intermediate stage includes a composite transistor of Darlington configuration following said controlled transistor.
19. A power amplifier as defined in claim 1 wherein said input, intermediate and power stages form part of an integrated module.
